GEORGE B. THOMAS, OF BRIDGEPORT, CONNECTICUT, ASSIGNOR TO THE PERKINS ELECTRIC SWITCH MANUFACTURING COMPANY, OF BRIDGEPORT, CONNECTICUT, A CORPORATION OF CONNECTICUT.

ELECTRIC SWITCH.

971,419.

Specification of Letters Patent. Patented Sept. 27, 1910.

Application filed December 17, 1908. Serial No. 468,041.

To all whom it may concern:

Be it known that I, GEORGE B. THOMAS, a citizen of the United States of America, and residing in the city of Bridgeport, in 5 the county of Fairfield and State of Connecticut, have invented certain new and useful Improvements in Electric Switches, of which the following is a specification.

My invention relates to electric switches 10 and particularly to the spindle for carrying the contact piece, the object of my invention being to provide a spindle having the end which carries the operating handle or key effectively insulated from the end carrying 15 the contact piece or coming into contact with electrically live parts of the switch mechanism.

In the accompanying drawings in which 20 my invention is shown applied to a spindle for an incandescent lamp socket, Figure 1 is a side elevation of the switch spindle and key; Fig. 2 is a broken elevation of the key end on a larger scale; and Fig. 3 is a perspective of the spindle with the parts detached and in position for assembly.

The device commonly employed for 25 insulating the operating key for the switch spindle is to thread or force upon the round spindle a metal bushing lined with insulation and thread the key upon the bushing. This is a very unsatisfactory method however since the heat of the lamp is often sufficient to so soften the insulation that the bushing merely swivels upon the spindle 35 when the key is turned, and the switch mechanism is thus rendered inoperative.

The present invention provides an improved means for insulating the key A from 40 the spindle and comprises a metallic shell 5 of angular shape, carrying a threaded stem 6 on which the key may be screwed. This stem may be made separate from the shell as shown in Fig. 3 and provided with a head 7 of angular contour conforming to 45 that of the shell and adapted to fit within the latter, the stem passing through a perforation therein.

An insulating washer 8 preferably of vul-

canized fiber or other insulating material which will not soften under the heat of the 50 socket, separates the stem from the angular end of the switch spindle 9, the latter being preferably spread to form a head 10 of angular outline. A washer 11 preferably of the same material shaped externally to fit 55 the shell and internally to fit the angular end 10 of the switch spindle not only insulates the latter from the sides of the shell 5 but centers it with relation to the key 55 stem 6. A third washer 12 is fitted above 60 the head 10 and within the shell, and the whole is then rigidly united by rolling over the edges of the shell under pressure.

It will be readily seen that by this construction, the danger of the key stem swiveling upon the switch spindle, is reduced to a minimum since an insulating medium may be employed which is not affected by the heat to which it is likely to be subjected. Furthermore owing to the angular outline 70 of the shell with which the key stem is rigid, on the one hand, and the angular head of the switch spindle on the other, there is a bite between the parts even though a softening insulation material be employed, 75 and this is heightened by the unifying pressure exerted by the rolled over edges of the shell.

It is obvious that the precise construction illustrated may be departed from without 80 evading the scope of the invention and that the device may be applied to switch spindles other than for sockets and I do not limit myself to the precise structure shown.

I claim as my invention:

A spindle for switch mechanism comprising 85 a spindle with angled head on one end, an angled shell surrounding said head and perforated in line with said spindle, a threaded key stem projecting through said 90 perforation and provided with an angled head fitting within said shell, an insulating washer separating said key stem from the switch spindle, a washer surrounding the head on said spindle and separating the 95 same from said inclosing shell, a washer

threaded over the switch spindle and juxtaposed to the head thereon, the edges of said angled shell being rolled over upon the last mentioned washer and serving to lock 5 said parts together, substantially as described.

In testimony whereof I have signed my

name to this specification, in the presence of two subscribing witnesses.

GEORGE B. THOMAS.
